(57) **CLAIM**

The ornamental design for a panel for automotive monitor, as shown and described.

DESCRIPTION

FIG. 1 is a top front right perspective view showing a panel for automotive monitor showing the new design;
 FIG. 2 is a top front left perspective view thereof;
 FIG. 3 is a front view of the first embodiment thereof;
 FIG. 4 is a left side view of the first embodiment thereof;
 FIG. 5 is a right side view of the first embodiment thereof;
 FIG. 6 is a top view of the first embodiment thereof;
 FIG. 7 is a bottom view of the first embodiment thereof; and,
 FIG. 8 is a cross-sectional view taken along the line 8--8 in FIG. 3.
